MOTION PICTURE/SLIDE PROJECTOR CONSOLE

Allan B. Corderman, 161 Ramblewood Road, and Philip
B. Flagler, 670 Chester Ave., both of Moorestown,
N.J. 08057

Filed June 19, 1973, Ser. No. 371,358

Term of patent 14 years

Int. Cl. D16—02

U.S. Cl. D61—1 N

FIG.1

FIG. 2

FIG. 3

FIG.4

FIG.5

FIG. 1 is a front perspective view of a motion picture/slide projector console showing our new design;

FIG. 2 is a top plan view thereof;

FIG. 3 is a front elevational view thereof;

FIG. 4 is a left side elevational view thereof; and

FIG. 5 is a right side elevational view thereof.

The rear, not shown, is plain and unornamented.

We claim:

The ornamental design for a motion picture/slide projector console, substantially as shown.
